[57] **CLAIM**

The ornamental design for a circular cutting blade, as shown and described.

DESCRIPTION

FIG. 1 is a front elevational view of the circular cutting blade showing our new design;

FIG. 2 is an end view of a portion of the circumference thereof, the entire circumference having an identical configuration;

FIG. 3 is a rear elevational view of the circular cutting blade shown in FIG. 1; and,

FIG. 4 is a cross sectional view taken along line 4—4 shown in FIG. 1.

The broken line illustration of the central aperture is for illustrative purposes only and forms no part of the claimed design.
